United States Patent Office

Des. 214,604
Patented July 1, 1969

214,604

STOVE

Harry Edward Schrock, 14520 Condon,
Lawndale, Calif. 90260

Filed Dec. 22, 1967, Ser. No. 9,885

Term of patent 14 years

Int. Cl. D7—04

U.S. Cl. D81—10

Fig. 1.

Fig. 2.

Fig. 3.

Fig. 4

Fig. 5.

Fig. 6.

FIG. 1 is a perspective view of a stove of the present invention, with a flue indicated in broken lines and included for illustrative purposes only;

FIG. 2 is a top view thereof;

FIG. 3 is a bottom view thereof;

FIG. 4 is a front elevational view thereof;

FIG. 5 is a right side elevational view thereof; and

FIG. 6 is a rear elevational view thereof.

I claim:

The ornamental design for a stove, as shown and described.
